UNITED STATES PATENT OFFICE.

WILLIAM R. McKEEN, JR., OF OMAHA, NEBRASKA.

DESIGN FOR A CAR-BODY.

No. 38,786.

Specification for Design.

Patented Sept. 3, 1907.

Application filed January 17, 1907. Serial No. 352,837. Term of patent 14 years.

To all whom it may concern:

Be it known that WILLIAM R. McKEEN, Jr., a citizen of the United States, residing at Omaha, in the county of Douglas and State of Nebraska, hath invented a new, original, and ornamental Design for a Car-Body, of which the following is a specification, reference being had to the accompanying drawing, forming a part thereof.

The figure is a plan view of a car body showing my new design.

I claim:

The ornamental design for a car body as shown.

WILLIAM R. McKEEN, JR.
